UNITED STATES PATENT OFFICE.

CHURCHILL HUNGERFORD, OF PHILADELPHIA, PENNSYLVANIA.

FILTER.

SPECIFICATION forming part of Letters Patent No. 707,333, dated August 19, 1902.

Application filed May 9, 1902. Serial No. 106,545. (No model.)

To all whom it may concern:

Be it known that I, CHURCHILL HUNGERFORD, a citizen of the United States, residing in the city and county of Philadelphia, State 5 of Pennsylvania, have invented a new and useful Improvement in Filters, of which the following is a specification.

My invention consists in providing a filter with a sand-valve which is adapted to automatically adjust itself to the flow of water therethrough.

It further consists of novel details of construction, all as will be hereinafter fully set forth.

15 Figure 1 represents a partial sectional view and partial elevation of a portion of a filter embodying my invention. Fig. 2 represents a top plan view of a valve employed, showing a portion broken away. Fig. 3 represents 20 a bottom plan view thereof.

Similar letters of reference indicate corresponding parts in the figures.

Referring to the drawings, A designates a tank or compartment which is provided with 25 the nipple B and with the plate or partition C, which has suitable openings therethrough, said plate dividing the tank A into separate chambers.

D designates sand-valves, which are connected, by means of the threaded pipes E, with the partition C, whereby the said valves are held in position. The said valves D consist each of a body comprising, respectively, top and bottom plates F and G, preferably spring-35 brass, and between these plates is the side wall of said body, the same consisting of a ring or annulus H, to which the plates are suitably attached, in the present instance by the screws J. Between said plates and rings 40 at the place where the same are secured together are washers K, which hold the plates a slight distance away from the ring, forming spaces or ports L and M therebetween. In the plates are the cuts, slits, or other means 45 of severance, as at N, which extend from the periphery thereof toward the center in such a manner as to leave portions of said plates movable, said portions producing wings or flaps P, which are adapted to be automatically raised and lowered, as will be further explained.

Q designates the sand or filtering substance,

which is adapted to be placed in the tank on the valves D and the partition C, and the weight thereof resting on the upper plates or 55 covers F of the bodies of the valves causes the same to partially or nearly close the ports L.

The operation is as follows: The water passes through the sand, and as the upper ports are substantially closed, excepting adjacent to the washer, it enters the valve through the lower ports and said spaces. As the area of the inlet through the valves is reduced because of the partially-closed upper ports, the water passes speedily through the 60 open ports, and the tendency of the same to choke is reduced. When it is desired to wash the filter, water which may be unfiltered is passed through the opening B upwardly and through the pipes E and the ports L and M. 70 This lifts the flaps and causes the sand to rise, and thus said flaps spring back to their former position, opening the upper ports, and the water passes through the valve more easily and rapidly, it being seen in this manner that 75 should any foreign substance have become lodged in the ports of the valve, thereby causing a stoppage, the pressure of the water will force the same through the valve into the tank A, thus relieving the valve and rendering 80 the latter self-clearing.

It will be evident that various changes may be made by those skilled in the art which will come within the scope of my invention, and I do not, therefore, desire to be limited in every 85 instance to the exact construction herein shown and described.

Having thus described my invention, what I claim as new, and desire to secure by Letters Patent, is—

1. In a sand-valve for filters, a body having a top plate, a side wall, and a port between said wall and plate, said plate being movable in part as a flap, whereby said port is adapted to be automatically reduced in area during 95 the filtering process and which is automatically increased in area during the cleansing process.

2. In a sand-valve for filters, a body formed of a plate, a side wall, and a port between said wall and plate, said plate being movable in part as a flap which is adapted to be automatically reduced in area during the filtering process, whereby the water is compelled to

flow at a rapid rate through the port by reason of said decreased area, reducing the tendency of any foreign matter remaining therein, and said port being adapted to be automatically opened during the cleansing process by reason of the mobility of said plate of the valve thereby increasing the area to such an extent that the water passing therethrough is not materially retarded by friction, nor is it possible for any foreign substances to be held in said port.

3. A sand-valve for a filter consisting of a plate and a side wall with a port between said wall and plate, said plate having a portion of the same severed forming a movable flap ¹⁵ which is integral with said plate and adapted to regulate the area of said port.

CHURCHILL HUNGERFORD.
